REFRIGERATING SYSTEM

Damian L. Reynolds, Hillsboro, Calif.

Application May 2, 1932, Serial No. 603,699

23 Claims. (Cl. 62—20)

This invention relates to refrigerator cars, and more particularly to such cars that utilize an ice compartment or bunker at one or both ends of the car. Such bunkers are separated from the cargo compartment by a suitable bulkhead structure, so formed as to permit circulation of cold air from the bunker into the cargo space.

This circulation, however, is apt to be somewhat inefficient, as it is secured mainly by differences in the density of cold and warm air. Furthermore, the liquid or brine resulting from the melting ice is usually discharged immediately outside of the car, although it is still capable of absorbing a large quantity of heat. In my prior application, Serial No. 362,674, filed May 13, 1929 for Refrigerator car, I describe a system in which the melted liquid or brine is retained for a period in a deep pan in the bottom of the bunker in order to permit it to absorb heat. This application is a continuation in part of said prior application.

It is one of the objects of my present invention to provide a refrigerator car that is an improvement over the said earlier application.

It is another object of my invention to make it possible to pass the liquid brine collected in the pan to cooling coils or pipes suitably arranged in the cargo compartment, prior to its discharge, to enhance the refrigerating effect. This circulation or passage of the brine is rendered possible by the aid of a pumping or suction device which can readily be attached to be operated from mechanism already installed on the car, for other purposes (such as gas pressure for air brakes or steam or fluid pressure in general), or indeed the operation can be performed by the motion of the car itself (such as a pendulum or a transmission from one of the axles).

It is another object of my invention to make it possible to operate the circulating apparatus intermittently, as determined by a sufficient accumulation of refrigerant, either fluid or liquid, such as brine in a collector or pan which may be arranged below the ice bunker.

My invention possesses many other advantages, and has other objects which may be made more readily apparent from a consideration of several embodiments of my invention. For this purpose I have shown a few forms in the drawings accompanying and forming part of the present specification. I shall now proceed to describe these forms in detail, which illustrate the general principles of my invention; but it is to be understood that this detailed description is not to be taken in a limiting sense, since the scope if my

invention is best defined by the appended claims.

Referring to the drawings:

Figure 1 is a side elevation of a portion of a refrigerator car embodying the invention, the ice compartment being shown in section; 5

Fig. 2 is a diagram of a complete installation showing the circulating system in the cargo compartment;

Figs. 3, 4, and 5 are diagrams illustrating various forms of the circulating pipes that may be utilized as desired in my system; 10

Fig. 6 is an enlarged detail sectional view, showing the structure of some of the control apparatus;

Fig. 7 is a detail section, taken along plane 15 1—1 of Fig. 6;

Fig. 8 is an enlarged view, mainly in section, of the apparatus for establishing the circulation of the liquid refrigerant or liquor before it is discharged; and 20

Fig. 9 is a view similar to Fig. 8, showing a modified form of apparatus.

In Fig. 1 there is shown a car 11, having heat insulated walls, floor and roof, constructed in any suitable or usual manner. Wheels 12 are 25 also diagrammatically indicated, as well as the main floor beam structure 13. At one or both ends of the car 11, there is provided an ice bunker 14, above which the usual hatch structure 15 is indicated. 30

At the bottom of the ice compartment 14, there is provided a pan or container 16 (Figs. 1, 2 and 6) that can hold a large amount of liquid or liquor resulting from the melting of the ice in bunker 14. The liquid or liquor is formed due to the fact that usually common salt or other chloride salts may be used to lower the temperature at which the ice melts. As disclosed in my prior application, the upper edges of this pan are turned inwardly as at 17 to provide overhanging ledges, hampering the slopping over of liquid when the car is jolted or jarred or suddenly started or stopped. 35

The arrangement is such that the liquid or liquor is caused to accumulate for a comparatively long period in container 16, such as six or seven hours. In this way, the liquid or liquor is utilized to absorb additional heat; and furthermore, prior to its ejection out of the car, the liquid is passed into the cargo compartment 18 (Figs. 1, 3, 4, and 5), as through a series of pipes, to absorb heat directly from this compartment. Preferably, these pipes for conducting the liquid or liquor to the cargo compartment are arranged 50 55

near the ceiling where the hot air tends to accumulate. Thus as shown most clearly in Figs. 1, 2, and 6, the liquid or liquor is caused, during ejection, to flow upwardly through a discharge pipe 19, extending almost to the bottom of container 16, through an upright pipe 20, convolutions 21 at the top of the cargo space 18, downwardly through pipe 22, and out through the discharge 23. The manner in which this intermittent discharge is automatically accomplished will be later described.

Any of a number of forms of convolutions adjacent the top of the cargo space can be used; several are shown in diagram form in Figs. 3, 4, 15 and 5. In Fig. 3, each ice compartment 14 has an upright pipe branching at 24 to conduits 25, 26 extending across to about the center of the car; then after several convolutions, they recombine at 27 to downwardly directed pipe 22. 20 In Fig. 4, the convolutions 27' extend from each ice bunker 14 for the full length of the cargo space, but on opposite sides respectively of a longitudinal center line.

In Fig. 5, only the left hand bunker 14 is shown 25 as providing the circulatory liquid. The convolutions 28 here are distributed uniformly over the entire area of the cargo space, and lead to the pipes 20, 22.

It is thus apparent that the cargo space can 30 be quite uniformly cooled and particularly where there is apt to be the greatest accumulation of heat. This is in contradistinction to the old systems whereby warm air enters the ice bunkers at the top and near the end of the car only, while 35 cold air escapes from below the ice and at the end of the car only.

In the present instance, the control of the circulation and final ejection of the refrigerant, liquid or liquor is obtained by a float valve mechanism responding to the accumulation of liquid or liquor of sufficient quantity. This mechanism is most clearly disclosed in Figs. 1, 2, and 6. 40 It includes a large float 29 in tank or container 16, that virtually covers the whole area of the 45 tank and that therefore also tends to keep the liquid or liquor from excessive motion. However, in lieu of such a float mechanism, other mechanism, operating in response to the accumulation of liquid or to the condition of the circulating system could be used.

When the liquid or liquor in tank 16 reaches a definite level, the float 29 reaches a position such that the bottom of a slot 30 on an upright member 31 fastened to the float, engages a pin 32. This pin is located at the end of a link 33, pivoted to a lever 34. This lever in turn is pivotally mounted at 35 on a standard 36 which may be conveniently supported on pipe 22. It is apparent that further rise of float 29 will rotate lever 60 34 in a counterclockwise direction, and this motion is utilized to operate valves for permitting the container 16 to discharge.

Thus there is a valve structure 37 (Figs. 1, 2, and 6) which normally closes the passage from pipe 19 to pipe 20. This valve structure includes a body that has a flange 38 serving as a support for the valve, as well as for a valve structure 39 for controlling the discharge outlet 23. For this purpose, flange 38 is securely fastened to the side 70 of the container 16. Extending from this flange is an elbow 39 for the pipe 19, providing a connection into the valve structure 37.

This valve structure has a seat 40 cooperating with a closure 41. A stem 42 (Figs. 6 and 7) extends from the closure downwardly and through

a stuffing box 43. At the end of the stem there is a clevis 44 having a lost motion connection with a lever 45 pivoted at 46 on flange 38. The end of the lever 45 is pivoted to a link 47 joined to an intermediate point of operating lever 34. 5 The lost motion connection is provided by slots 48 in clevis 44, and a transverse pin 49 carried by lever 45 and entering the slots.

It is thus apparent that, as lever 34 rises due to the force exerted upon it from the float 29, 10 link 47 is pulled upwardly, lever 45 rises, and after a short movement, urges stem 43 upwardly to open the valve 37, and to establish communication between pipe 19 and pipe 20. The same motion of lever 34 serves to open the discharge valve 15 closure 50 in outlet 23, to permit the liquid or liquor circulating in pipes 21 to be discharged outside of the car. Thus valve closure 50 has a stem 51 extending through the stuffing box 52 and carrying a clevis 53 in which pin 49 is engaged. In this instance there is no lost motion connection between clevis 53 and lever 45, whereby it is ensured that the vent 23 is opened before valve 37 is opened. This order of opening the valves is advantageous for the reasons now 25 to be explained.

In order to lift the liquid or liquor from tank 16 upwardly to pipe 21, it is necessary to utilize some pumping arrangement or its equivalent. The means for accomplishing this in the present 30 instance, is apparatus for establishing a siphon action, as by producing a partial vacuum above tank 16, in a manner to be later described. Since discharge 23 is considerably below this tank, it is apparent that the siphon will completely empty the tank, once it is established. It is for this reason that care is taken to open discharge 23 before valve 37 is opened. If there should be a slight leak near the bottom of the system, and valve 50 should open last, the siphon 40 action may be broken, or indeed, a reverse siphon may tend to be established.

Before describing the apparatus for establishing the siphon action when the valves open, it is desirable to complete the description of the 45 float mechanism. Referring again to Fig. 6, the arrangement is such that the friction of the parts, such as the motion of the valve stems in the stuffing boxes, serve to retain the mechanism in open or closed position once such a position is 50 established. Thus when pin 32 is pushed upwardly by float 29, the valves 37, 23 remain open even after float 29 recedes as the tank 16 empties. After the float, however, reaches a lower position corresponding to substantial emptying of tank 16, 55 the upper end of slot 30 engages pin 32 and positively recloses the valves by pulling lever 34 downwardly by the weight of the float.

One manner in which the siphon is established is illustrated in Fig. 8. In this case, there is 60 shown a suitable reciprocating vacuum pump 54, of any convenient form. For example, it may be provided with a reciprocating piston 55 having a rod 56, for reciprocating the piston. Each of the heads 57, 58 of the pump is provided with a 65 port 59, 60 and a one-way or check valve 61, 62. A T connection 63 connects to a vacuum pipe 64 (Figs. 2 and 8) which connects to the top of the system; for example, above pipe 20. As piston 55 reciprocates, it alternately pulls a vacuum from 70 pipe 64 through ports 59 and 60, past the respective valve 61 or 62. However, upon a return stroke, the piston urges the air collected through the spring pressed outlet valve 65, 66, attached to the upper end of the pipe 67 or 68 leading re- 75

spectively to the ports 59, 60. Since this type of vacuum mechanism is well known, further description thereof is unnecessary.

Since a vacuum is created at or near the top 5 of the system by this arrangement, it is apparent that the liquid or liquor will rise through pipe 20 and a siphon will be established, passing the liquid or liquor through pipes 21 and out at the foot valve 23. The difference in the level of intake and discharge (corresponding to the height 10 of the level in tank 16 above valve 23) is small enough to ensure a rather slow rate of discharge, to give ample opportunity for the liquid or liquor to absorb heat while passing through pipes 21.

15 Furthermore, the arrangement is such that as soon as the siphon is established, the pump is stopped. This arrangement will now be described, in connection with the mechanism for reciprocating the piston rod 56.

20 The rod 56 is shown as directly joined to a reciprocating piston 69 in a cylinder 70. This is an air cylinder, so arranged that the compressed air used for the brake mechanism urges the piston 69 in either direction. For example, at the 25 left hand end of the cylinder 70 there is an air inlet 71 and an air outlet 72. Correspondingly at the right hand end, there is an air inlet 73 and an air outlet 74. When air under pressure is passed through inlet 71, to urge piston 69 to 30 the right, the passage 73 at the right is active to carry away the air on the right of piston 69; and passageways 72, 74 are blocked. However, after a definite movement, the air connections are changed to block passages 71, 73 and to render passageways 72, 74 active, causing piston 69 to move to the left. This reciprocating cycle is repeated until the supply of air is interrupted in a manner to be described.

35 The control of the passages 71, 72, 73, 74 can be accomplished by a piston valve 75 sliding in a housing 76 and operated in accordance with the operation of piston 69. At the particular instant shown, air passes to the left of piston 69 urging toward the right, through the following 40 passages: from pipe 17 connected to the train air line 78, through cap 79, opening 80 in housing 76, annular passage 81 of valve 75, and passage 71. At the same time, air is exhausted from the right hand of piston 69, through passage 73, 45 housing 76, and vent 82 to the air. Passages 72 and 73 are interrupted by the valve 75 resting over the corresponding openings in housing 76.

50 Now as piston 69 moves to the right, it will at the extremity of its stroke, push valve 75 to the right, by the aid of collar 83 on rod 84 passing through valve 75. The movement of valve 75 continues until it blocks passages 71 and 74, and uncovers passages 72 and 73. In that position, train air will be passed through passage 73 to move piston 69 to the left, and passage 72 will be uncovered to exhaust air from the left hand of piston 69, through vent 85. Upon sufficient movement of piston 69 to the left, collar 86 on stem 84 will move valve 75 to the position shown, 55 and the cycle is repeated.

55 The pump mechanism just described operates so long as air is permitted to pass to passage 80 from pipe 17. However, this passage is interrupted just as soon as a siphon is established. 60 For example, a valve closure 87 on a stem 88 is arranged to close the top of passage 80, when brine is present in the discharge pipe 23. To accomplish this purpose, stem 88 is shown as 65 guided in a packing gland 89 for cap 79, and as 70 joined to a rod 90, fastened to a corrugated dia-

75 phragm 91. This diaphragm is arranged to be acted upon by the weight of the column of brine which is in the system while the siphon is operating, to depress the rod 90 and close opening 80. Thus diaphragm 91 is held tightly at its edges in the two stationarily supported casing halves 92 and 93. The upper half 92 is connected as by elbow 94 and conduit 95 to discharge 23 so that the weight of the liquid or liquor while the siphon is active, is effective on the upper surface 10 of the diaphragm.

75 Normally, however, a compression spring 96 acts on a collar 97 on stem or rod 90 to hold the rod up and closure 87 away from closing position. Spring 96 is conveniently accommodated 15 in a tubular extension 98 of casing half 93, and its lower end rests on a plug 99 closing the extension and serving as an additional guide for rod 90.

80 Ordinarily, spring 96 is adjusted so that a substantial preponderance of pressure is necessary to close valve 87. This ensures against the possibility of an imperfect siphon action which may occur if valve 87 is closed too soon, causing the retention of air in conduits 21. Pipe 64 is, however, connected to pipe 20 at a point considerably above diaphragm 91, to provide a sufficient head of liquid in the column formed by pipe 20 85 sufficiently to compress spring 96 only when a full siphon action is initiated.

85 By reference to Fig. 2, the operation of the system can now be briefly explained. While brine is collecting in tank 16, float 29 resting on top of the accumulated liquid, is in an intermediate position, pin 32 being in an intermediate 90 point on slot 30. The valves 23, 31 are closed, and air is merely pumped out from pipes 21 by pump 56. Valve 87, controlling the pump operation, is open and held in that position by spring 96. As soon as the accumulation of liquid causes 95 float 29 to operate lever 34, valves 37, 23 are opened, and the vacuum pump 54 now operates to establish the siphon, by evacuating the air in pipes 21. When this is accomplished, the diaphragm 91 is depressed, closing opening 80 and 100 stopping the pump. The brine is now ejected from valve 23 by the siphon action. When this ejection corresponds to a lowering of float 29 to pull lever 34 downwardly, valves 37, 23 are closed, and the siphon action ceases. The cycle is then 105 repeated upon an additional sufficient accumulation of brine, or other refrigerant or liquor in tank 16. Should the siphon break for any reason, during the period of ejection, closure 87 moves to open position, and vacuum pump 54 is 110 again effective to reestablish the siphon.

115 If desired, an air exhaust valve 108 (Fig. 2) can be provided in the vacuum pipe 64, as well as a siphon fill valve 101 in pipe 85, which may be used for testing or for filling the system. Thus 120 with valve 108 open, the valve 101 can be used to fill the system, after which valve 108 must be closed.

125 In Fig. 9, an alternative form of mechanism for driving the vacuum pump 54 is disclosed. In this case, a pendulum 102 is shown as suspended on bracket 103 on the pump head 58, which swings as the car moves, and its oscillations are used to reciprocate the piston 55. Thus a link 104 can connect an intermediate point of 130 the pendulum 102 to the rod 56. An adjustable weight 105 is provided for controlling the period and force of the oscillations.

135 In this instance, the pumping action is controlled as before, by the head of the liquid in the 140

pipes when the siphon is started. Thus the vacuum 95, becoming filled with liquid or liquor when the action starts, is connected to the upper end of a diaphragm casing 106. This liquid depresses diaphragm 108, and therefore the rod 107 connected thereto, against the action of the compression spring 109. This rod 107 carries a valve closure 110 in a sealed chamber 111 that is interposed in the vacuum line 64. Rod 107 extends into chamber 111 through gland 112 and is opposed to the bottom opening of the chamber. Valve closure 110 closes this opening and interrupts communication from pump 54 to pipe 64, when diaphragm 108 is depressed, and the pump 54 becomes ineffective. The diaphragm arrangement 106, 107, 108, 109 is similar in action to that described in connection with Fig. 8.

In order to ensure against corrosion or oxidation of those parts in contact with the refrigerant, it is preferable to make all or some of such parts of material resistant to such corrosion or oxidation. This may include tank 16, as well as the conduits 20, 21, valves 23, 37, 39 and their controls.

Should the siphon mechanism for any reason fail of operation, an extra safeguard for emptying the tank 16 upon excessive accumulation, can be provided. This is illustrated in Fig. 6. A discharge pipe 106 extends through the floor of the car and up into the tank 16, the upper end thereof corresponding to the extreme limit of accumulation. Surrounding this pipe is a tube 107, closed at the top but having an opening 108 near the bottom to permit liquid from tank 16 to rise therein. As soon as the liquid level in tank 16 reaches the top of pipe 106, through the annular space between tube 107 and pipe 106, a siphon is established, emptying the tank completely outside of the car. In this way, accidental flooding of the car floor is prevented. It is to be understood, however, that this mechanism is inactive in the range of operation of float 29.

I claim:

1. In an ice refrigerator car having a cargo compartment and an ice bunker, said compartment and ice bunker being in air circulating relationship, means for collecting the liquid resulting from the melting ice, means for circulating the collected liquid in the cargo compartment, and means, acting in response to the accumulation of a definite amount of liquid, for initiating the operation of the circulating means.

2. In an ice refrigerator car having a cargo compartment and an ice bunker, said compartment and ice bunker being in air circulating relationship, means for collecting the liquid resulting from the melting ice, means intermittently active to circulate the said collected liquid in the cargo compartment, and a float mechanism responsive to a definite rise or fall of level of the collected liquid for controlling said liquid circulating means.

3. In an ice refrigerator car having a cargo compartment and an ice bunker, said compartment and ice bunker being in air circulating relationship, means for collecting the liquid resulting from the melting ice, means for circulating the collected liquid in the cargo compartment, and means, acting in response to the accumulation of a definite amount of liquid, for initiating the operation of the circulating means, comprising means ensuring that said circulating means remains active until the accumulated liquid is reduced to a definite amount.

4. In an ice refrigerator car having a cargo compartment and an ice bunker, said compartment and ice bunker being in air circulating relationship, means for collecting the liquid resulting from the melting ice, means for passing the liquid into the cargo compartment upon a definite accumulation, and means ensuring the continuation of the passage of liquid until the remaining collected liquid is reduced to a definite amount.

5. In an ice refrigerator car having a cargo compartment and an ice bunker, means for collecting the liquid resulting from the melting ice, means intermittently acting to establish a siphon action to pass the liquid to the cargo compartment, and means responsive to the establishing of the siphon to render this establishing means ineffective.

6. In an ice refrigerator car having a cargo compartment and an ice bunker, means for collecting the liquid resulting from the melting ice in a space below the bunker, a conduit leading from the space to a higher level in the cargo compartment, vacuum producing means acting on a high part of the conduit to produce a siphon action therethrough, and means for rendering said vacuum producing means ineffective in response to the establishment of the siphon action.

7. In an ice refrigerator car having a cargo compartment and an ice bunker, means for collecting the liquid resulting from the melting ice in a space below the bunker, a conduit leading from the space to a higher level in the cargo compartment, vacuum producing means acting on a high part of the conduit to produce a siphon action therethrough, and means for rendering said vacuum producing means ineffective in response to the establishment of the siphon action, comprising a valve closure acted upon by the weight of the siphon column to interrupt the communication between the vacuum producing means and the siphon.

8. In an ice refrigerator car having a cargo compartment and an ice bunker, means for collecting the liquid resulting from the melting ice in a space below the bunker, a conduit leading from the space to a higher level in the cargo compartment, and vacuum producing means acting on a high part of the conduit to produce a siphon action therethrough, comprising a pump and fluid operated means for operating the pump.

9. In an ice refrigerator car having a cargo compartment and an ice bunker, means for collecting the liquid resulting from the melting ice in a space below the bunker, a conduit leading from the space to a higher level in the cargo compartment, and vacuum producing means acting on a high part of the conduit to produce a siphon action therethrough, comprising a pump, and a pendulum for operating the pump.

10. In an ice refrigerator car having a cargo compartment and an ice bunker, means for collecting the liquid resulting from the melting ice in a space below the bunker, a conduit leading from the space to a higher level in the cargo compartment, vacuum producing means acting on a high part of the conduit to produce a siphon action therethrough, a mechanism for driving the pump, and means responsive to the establishment of the siphon for rendering said mechanism ineffective.

11. In an ice refrigerator car having a cargo compartment and an ice bunker, means for collecting the liquid resulting from the melting ice in a space below the bunker, a conduit leading

from the space to a higher level in the cargo compartment, vacuum producing means acting on a high part of the conduit to produce a siphon action therethrough, a mechanism for driving the pump, and means responsive to the establishment of the siphon for rendering said mechanism ineffective, comprising a valve closure operated by the weight of the siphon column.

12. In an ice refrigerator car having a cargo compartment and an ice bunker, means for collecting the liquid resulting from the melting ice, a conduit leading from the collected liquid, into the cargo compartment, and finally out of the car, a valve controlling the intake of liquid into the conduit, another valve controlling the discharge of liquid from the conduit, and means responsive to a definite accumulation of liquid to open the valves and to initiate a siphon action through the conduit.

13. In an ice refrigerator car having a cargo compartment and an ice bunker, means for collecting the liquid resulting from the melting ice, a conduit leading from the collected liquid, into the cargo compartment, and finally out of the car, a valve controlling the intake of liquid into the conduit, another valve controlling the discharge of liquid from the conduit, and means responsive to a definite accumulation of liquid to open the valves in succession, the intake valve opening last, and to initiate a siphon action through the conduit.

14. In an ice refrigerator car having a cargo compartment and an ice bunker, means for collecting the liquid resulting from the melting ice, a conduit leading from the collected liquid, into the cargo compartment, and finally out of the car, a valve controlling the intake of liquid into the conduit, another valve controlling the discharge of liquid from the conduit, and means responsive to a definite accumulation of liquid to open the valves and to initiate a siphon action through the conduit, comprising a float, and a member movable by the float to open said valves when the liquid reaches a definite level.

15. In an ice refrigerator car having a cargo compartment and an ice bunker, means for collecting the liquid resulting from the melting ice, a conduit leading from the collected liquid, into the cargo compartment, and finally out of the car, a valve controlling the intake of liquid into the conduit, another valve controlling the discharge of liquid from the conduit, and means responsive to a definite accumulation of liquid to open the valves and to initiate a siphon action through the conduit, comprising a float, and a member movable by the float to open the discharge valve and the intake valve in succession when the liquid reaches a definite level.

16. In apparatus of the character described, a container for a refrigerant liquid, a conduit for passing the liquid to a space to be cooled, a vacuum producing means for establishing a siphon action for ejecting the liquid through the conduit, and means controlling said vacuum producing means, to render it ineffective when the siphon is established, and to render it effective when the siphon breaks.

17. In apparatus of the character described, a container for a refrigerant liquid, a conduit for passing the liquid to a space to be cooled, a constantly operating vacuum producing means for establishing a siphon action for ejecting the liquid through the conduit, and including a vacuum connection to the conduit, means responsive to the establishment of the siphon for interrupting

said connection, and responsive to a break in the siphon for reestablishing said connection.

18. In a refrigerator car having a cargo compartment and an ice bunker, means for collecting the liquid resulting from the melting ice, a conduit above the liquid level and having an intake portion extending to the collecting means, said conduit passing into the cargo compartment, and means active upon reaching a definite level of collected liquid to initiate a siphon action through the conduit.

19. In a refrigerator car having a cargo compartment and an ice bunker, means for collecting the liquid resulting from the melting ice, a conduit above the liquid level and having an intake portion extending to the collecting means, said conduit passing into the cargo compartment, and means active upon reaching a definite level of collected liquid to initiate a siphon action through the conduit, comprising a float valve controlling the passage of liquid into the conduit, and a vacuum producing means effective at a level higher than the liquid in the conduit.

20. In a refrigerator car having a cargo compartment and an ice bunker, means for collecting the liquid resulting from the melting ice, a conduit above the liquid level and having an intake portion extending to the collecting means, said conduit passing into the cargo compartment, and means active upon reaching a definite level of collected liquid to initiate a siphon action through the conduit, comprising a float valve controlling the passage of liquid into the conduit, a valve operated in accordance with the float valve and controlling the ejection of the liquid from the conduit, and a vacuum producing means effective at a higher level in the conduit than the level of the collected liquid.

21. In an ice refrigerator car having a cargo compartment and an ice bunker, means for collecting the liquid resulting from the melting ice in a space below the bunker, a conduit leading from the space to a higher level in the cargo compartment, means initiating a siphon through the conduit from the space, and means for rendering said siphon initiating means ineffective in response to the establishment of the siphon action, comprising a movable control member for said initiating means, means yieldingly urging said member to cause said initiating means to function, and means whereby a head of liquid in the siphon column is opposed to said yielding means to cause the member to move to render the initiating means ineffective, said head being sufficiently large to ensure complete siphon action.

22. In an ice refrigerator car having a cargo compartment and an ice bunker, means for collecting the liquid resulting from the melting ice, a conduit leading from the collected liquid, into the cargo compartment and finally out of the car, a valve controlling the intake of liquid into the conduit, and means responsive to a definite accumulation of liquid to open the valve and to initiate a siphon action through the conduit.

23. In an ice refrigerator car having a cargo compartment and an ice bunker, means for collecting the liquid resulting from the melting ice, a conduit leading from the collected liquid into the cargo compartment and finally out of the car, a valve controlling the discharge of the liquid from the conduit, and means responsive to a definite accumulation of liquid to open the valve and to initiate a siphon action through the conduit.
